(57) **CLAIM**

The ornamental design for a capsule as shown and described.

DESCRIPTION

1.1 : Perspective

1.2 : Perspective

1.3 : Top

1.4 : Front

1.5 : Front

1.6 : Left

The design relates to a capsule as shown in perspective, front view, top view and left-side view; the essential characteristics of this design reside in particular in the arcs of circles as well as the letter B surrounded by a circle, which are embossed on the upper part of the capsule.
